CLAIM

The ornamental design for a display screen with graphical user interface of a layered data visualization element, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of the display screen with graphical user interface of a layered data visualization element; and, FIG. 2 is an enlarged partial view of the design of FIG. 1, shown for clarity of illustration.

The outermost broken line showing the display screen and all other broken lines showing portions of the graphical user interface are included for the purpose of illustrating portions of the article and form no part of the claimed design.
